UNITED STATES PATENT OFFICE.

FRED G. MAYER, OF RICHMOND, INDIANA, ASSIGNOR TO STARR PIANO COMPANY, OF RICHMOND, INDIANA, A CORPORATION OF INDIANA.

AUTOMATIC STOP FOR PHONOGRAHS.

Application filed November 28, 1921. Serial No. 518,154.

To all whom it may concern:

Be it known that I, FRED G. MAYER, being a citizen of the United States of America, residing at Richmond, in the county of

5 Wayne and State of Indiana, have invented certain new and useful Improvements in Automatic Stops for Phonographs, of which the following is a full, clear, and exact description.

10 It is common practice to provide a phonograph, upon which disk records are played, with an automatic stop for arresting the rotation of the turn table carrying the disk at any desired point in the travel of the 15 tone arm, sound box and stylus from the outer edge of the disk towards the center. Usually this stop is provided with an adjustable lever which is encountered by a suitable stop on the tone arm when the 20 latter has reached a predetermined point near the center of the disk and the end of the spiral record, and which when thus engaged, is moved and thereby trips the stop mechanism which, in some cases, throws a 25 brake against the turn table and thereby arrests its rotation.

The invention, subject of my present application for Letters Patent, is an improvement in stop mechanisms of this character 30 and is characterized by the special construction and mode of operation of the parts comprising said mechanism. Being specific to such mechanism, the improvement will be most readily understood from the detailed 35 description of the drawings, which illustrate my new device which follows and with this purpose in view I now refer to said drawings which are hereto attached.

Figure 1, which is partly diagrammatic, 40 shows the details of the improved stop mechanism. The phonograph, as a whole including the tone arm, is not illustrated as these parts are, or may be, of conventional 45 and well known form and character and require, for purposes of the present case, no special illustration or description beyond reference to such parts as are herein shown.

Fig. 2 is a sectional view of a portion of the edge of the turn table.

The numeral 1 indicates the usual turn table of an ordinary phonograph, the other edge of which is turned down to form a flange 2.

Under this turn table, near its outer edge,

the stop mechanism proper is mounted on 55 the stationary top plate of the machine and this mechanism comprises the following parts—

A disk or metal plate 3 to which is pivoted at 4 a trip lever 5, to which is adjustably secured a stop lever 6, which may be turned by hand and set at any desired angle to the lever 5 about its pivotal point 7. A trip dog 8 pivoted to the plate 3 at 9 and connected by a spiral spring 10 to the trip 60 lever 5, and a cocking stop lever 11 pivoted to plate 3 at 12 and provided with a cam 13 at its end that engages with a suitably shaped portion of the edge of the trip dog 8.

The trip lever 5 is impelled to the right 70 by the tension of the spring 10 and its rearward movement is limited by a fixed stop 14. It is fashioned or provided with a hooked or otherwise properly shaped portion 15 to engage a notch or shoulder 16 on 75 the trip dog 8, and when the handle 11 is shifted to the right into the position shown by full lines, this lever 5 and the trip dog 8 are brought into engagement and locked together. The trip dog 8 contains a slot 80 through which projects a pin 17 that limits its movement about the pivotal point 9.

The movement of the handle 11 to the left is checked by a stop pin 18, and the trip dog plate 8 carries a rubber stop or brake 85 19 in position to engage and press upon the inner face of the flange 2 when the said plate is tripped.

The manner of setting and using this device is well understood by those familiar 90 with such mechanisms. The tone arm is turned to bring the sound box and stylus to a point in their path of movement at which it is desired to arrest the rotation of the turn table. The lever 6 is then set so 95 as to make contact with the tone arm or a stop thereon, and the tone arm then swung to the point where the stylus rests in the groove at the outer edge of the disk.

The stop is then set or cocked by shifting 100 the handle 11 to the full line position and thereby bringing the parts 5 and 8 into interlocking engagement. The motor is then started and the stylus following the spiral groove throws the tone arm towards the 105 center of the disk until the stop thereon strikes the lever 6 whereupon that lever is shifted to the position shown in dotted lines

with the result that the trip dog 8 is released from engagement with the lever 5 and the rubber stop or brake thrown against the flange 2 thus stopping the turn table.

5 The great majority of automatic stops for this purpose are not satisfactory or dependable for various reasons, and much ingenuity has been exercised in devising forms that could be always relied upon to perform their 10 allotted functions. The form I have herein shown and described answers all practicable requirements better than any which have come under my observation. It is simple in construction and is of such nature that 15 derangement of its parts or failure to properly operate are practically impossible. It is positive in its action and may or may not be used as occasion may require or suggest.

20 What I claim is—

1. A stop mechanism for phonographs comprising in combination, a base plate disposed under the turn table, a trip lever pivoted thereon, a cocking handle pivoted to the plate, a dog intermediate the trip lever, and cocking handle, pivoted to the plate, the edge of which is engaged by the cocking

handle and adapted thereby to be thrown to bring a shoulder in its edge into locking engagement with the trip lever, a spring for maintaining such engagement, and a brake carried by the pivoted dog and adapted to be thrown by the disengagement of the said trip lever and dog and into operation to arrest the rotation of the turn table. 30 35

2. A stop mechanism for phonographs comprising in combination, a base plate disposed under the turn table, a trip lever pivoted to said platen an adjustable stop lever carried by the trip lever, a cocking lever also pivoted to the base plate, a dog or plate intermediate the trip lever and cocking handle pivoted to the base plate, and having shoulders that are adapted to be engaged by the cocking lever and to engage with the trip lever respectively when said cocking lever is shifted, a brake carried by the dog to engage the turn table when the trip lever and dog are disengaged, and a spiral spring 40 45 connecting the trip lever and dog. 50

In testimony whereof I hereto affix my signature.

FRED G. MAYER.
